UNITED STATES PATENT OFFICE

2,403,155

PORTABLE HEATER

Thomas F. Spackman, Chicago, Ill., assignor to
Stewart-Warner Corporation, Chicago, Ill., a
corporation of Virginia

Application February 22, 1943, Serial No. 476,727

8 Claims. (Cl. 280—9)

1

My invention relates to a carriage for supporting a heating unit for providing ready portability to the unit and also for providing a solid support at the time the unit is being operated as a heater.

The object of my invention is the provision of means for very quickly and reliably changing the heater carriage from its rigid runner supports to its wheel supports, and vice versa.

Portable heaters for airports, particularly for airplanes in combat use, must be changed from one location to another without delay. Heaters of the type for which my support is intended weigh in the neighborhood of 300 pounds, and in order that they may be moved by one operator on snow or through mud or on dry ground or concrete runways, it is desirable that they be provided with broad based runners for use under one condition of movement as well as with wheels for use under the other condition of movement, the runners forming a base when the heater is in operation for warming airplane motors or cabins.

In accordance with my invention, the wheels are supported at the ends of swinging arms pivoted on the carriage frame and adapted to swing like a pendulum past a dead center in one direction against a spring stop which maintains the wheel treads below the base of the runners, and in the other direction against a stop which maintains the wheel treads above the base of the runners. To move the wheels from one position to the other, it is only necessary to lift the end of the carriage to such a height that the wheels in their lowermost position will miss the ground, then release a catch permitting the arms and wheels to swing about their pivotal support until they have passed dead center, and then release the lifted end of the carriage, whereupon the arms and wheels will be moved to their alternate positions in which they are located until again released.

My invention is illustrated in the accompanying three sheets of drawings, in which:

Fig. 1 is an elevation of the carriage and its supported heater mechanism with one wheel omitted and showing the remaining wheel in position for supporting one end of the carriage;

Fig. 2 is an elevation of a fragmentary part of the carriage and its supported heater mechanism in which one wheel is omitted and the remaining wheel is in its lifted position which it assumes when the carriage rests on its runners;

Fig. 3 is a fragmentary section taken on the line 3—3 of Fig. 1;

2

Fig. 4 is a fragmentary section taken on the line 4—4 of Fig. 1;

Fig. 5 is a fragmentary section taken on the line 5—5 of Fig. 4;

Fig. 6 is a fragmentary section taken on the line 6—6 of Fig. 4, illustrating the connection of the torsion shaft with the stub shaft for the wheel-carrying swinging arms;

Fig. 7 is a fragmentary section taken on the line 7—7 of Fig. 1; and

Fig. 8 is a fragmentary section taken on the line 8—8 of Fig. 1.

Referring more particularly to Fig. 1, the carriage comprises a frame composed of upper and lower lineal tubular members 10 and 11 located at each side of the carriage. The members 10 and 11 are rigidly attached to one another by vertical tubular members 12 and 13, preferably welded to the lineal members 10 and 11. The forward ends of the lineal members 10 and 11 are bent at right angles and extend across the front of the carriage where they are attached together by vertical members 14 and join with the members 10 and 11 at the opposite side of the carriage. A tubular handle attachment member 16 is welded to the member 11 at 17 and to the rear end of the member 10 at 18, there being a vertical tubular member 19 extending between the rear end of the lineal member 11 and a position 20 on a horizontal portion of the handle attachment member 16. A handle 21 formed of tubing sufficiently larger than the handle attachment member 16 to slip snugly over it has welded thereto a brace 23 attached to the vertical member 19 and the horizontal handle attachment member 16 by suitable means such as bolts 25 and 26. By removing these bolts the handle and the brace member 23 may be slipped rearwardly and thus removed to decrease the size of the carriage for shipping purposes.

A runner 30, slightly curved upwardly at one end and curved upwardly into a rocker at the other end, is attached to the frame members by means of a plate 31 by bolts 33 and 34 which extend through a Z-bar 35 which is welded to the lower frame member 11 as illustrated more clearly in Figs. 7 and 8.

The wheel-carrying swinging arm 37 has a channel-shaped cross section for rigidity and is pivoted at 38 to the plate 31, there being a stub shaft 40 suitably attached, preferably by welding, at the pivot location of the swinging arm 37. Securely riveted to the inner face of the swinging arm 37 is a hardened steel locking disc 43 whose face is concentric about the axis upon which the

3

arm 37 is mounted, except that it is provided with two rectangular notches 44 and 45, the notch 45 being in a proper position to hold the wheel 47 slightly above the plane of the base of the runner 30 when the swinging arm is rotated to the counter-clockwise position shown in Fig. 2 and in dotted lines in Fig. 1. A detent 50 which fits rather closely within either of the notches 44 and 45 in the locking disc 43, is pivoted on the bolt 34 which assists in securing the plate 31 to the Z-bar 35 carried by the lower frame member 11. A lever 52 is attached to the detent member 50 for swinging the detent in a clockwise direction in Fig. 1 about the pivot bolt 34 by lifting the forward end of the lever 52 against the tension of the spring 54. The shaft 40 has bearing rings 55 which journal it for rotation within a hub 56 rigidly secured to the plate 31. A C-spring 57 is snapped into a groove in the shaft 40 to form an abutment against the withdrawal of the shaft 40 from the hub 56.

Two housings 60 and 61 containing springs 62 and 63 are attached to the outside of the plate 31, the housings being provided with slots 64 and 65 shown in Figs. 7 and 8 for receiving the upper edge of the swinging arm 37. The slots 64 and 65 are of such size as to engage the swinging arm 37 somewhat snugly, and since the slots are at different levels, they serve to steady the swinging arm 37 and prevent its wabbling under the stresses applied to it when the wheels of the carriage strike obstacles on the roadway. The springs 62 and 63 are not of sufficient strength to support the load of the vehicle, but act merely to decrease the shock when the carriage is dropped onto the wheels at the time it is being shifted from its runner support to its wheel support.

The side of the carriage not shown in the drawings is provided with a swinging arm and wheel like those shown and described, except that the locking mechanism is omitted. The stub shaft for the swinging arm not shown is provided with a squared end like 67 fitting into the square ended tubular shaft 68. Thus the two arms and their carried wheels are required to swing together. The side of the carriage not shown is provided with springs like 62 and 63 and with slotted housings 60 and 61 which perform the same function as those illustrated.

The operation of the preferred embodiment of my invention just described is as follows: Assuming the carriage to be resting on the ground on its two runners 30, with the arms 37 holding the wheels 47 in raised position as shown in Fig. 2, and that the attendant desires to move the carriage to a remote position by rolling it on its wheels rather than by sliding it on the runners, he will grasp the cross bar forming a part of the frame at the front end of the carriage at the left in Fig. 1 and lift that end until the distance of the pivot point 38 for the arms 37 above the ground is greater than the diameter of the wheel 47. In lifting one end of the carriage, the rocker ends of the runners roll on the ground and the center of mass of the air heater and its associated tanks and other parts comes into a position approaching a lateral plane extending vertically from the point of contact with the ground. When the carriage is in this position, only a very slight effort is needed for steadyng the carriage. The attendant now removes one hand from the cross bar of the frame by which one end of the carriage has been raised, and with that hand lifts the free end of the lever 52, thus swinging the detent 50 about its pivot 34 and releasing the

notched disc 43 and its attached swinging arm 37. The swinging arms carrying the wheels 47 now drop by gravity, and since the shafts 40 and the hubs 56 are freely rotatable in the plates 31 of the frame, the wheels and swinging arms swing downwardly and forwardly like a pendulum past the lower dead center. As this happens, the attendant lowers the end of the carriage, throwing its weight upon the wheels which now become locked in their running position as shown in Fig. 1 by reason of the detent 50 snapping into the notch 44 in the hardened disc 43 through the influence of the spring 54. Since the two shafts 40 on opposite sides of the vehicle are attached together by means of their squared ends 67 and the hollow interconnecting shaft 68, the swinging arms and wheels on each side of the carriage move together from one position to the other. When the attendant desires to place the weight of the carriage back upon its runners, he again lifts the end of the carriage as before, lifts the lever 52 as before, and again drops the end of the carriage after the wheels have swung downwardly and rearwardly past the lower dead center. This causes the wheels and their supporting swinging arms to swing in a counter-clockwise direction in Fig. 1 with sufficient momentum to carry them a short distance above the ground level, whereupon the detent 50 again drops into the notch 45 so located as to hold the wheels 47 slightly above the ground as shown in Fig. 2.

In the operations as above described, the lever 52 is released by the operator as soon as the detent 50 is disengaged from the notch 44 or 45. The end of the detent thereafter engages the circular face of the member 43 until the other notch is brought into registering position for engagement by the detent automatically.

When the wheels are in the position shown in solid lines in Fig. 1, the attendant rolls the vehicle like a two-wheeled push-cart, and when the wheels are in the position shown in dotted lines in Fig. 1, the attendant pulls or pushes the carriage as a sled.

While I have shown and described a preferred embodiment of my invention, it will be readily understood by those skilled in the art that variations may be made in the construction disclosed without departing from the basic features of my invention. I therefore do not wish to be limited to the precise construction disclosed, but wish to include within the scope of my invention all such modifications and variations which will readily suggest themselves.

Having thus described my invention, what I claim as new and useful and desire to secure by Letters Patent of the United States is:

1. In a carriage, a pair of runners upwardly turned at the ends, a frame structure carried by the runners, a pair of swinging arms each pivoted at one end to opposite sides of the frame structure, a pair of wheels one mounted upon the swinging end of each of the swinging arms, a shaft extending across the carriage interconnecting the swinging arms, and means for locking the swinging arms releasably in either of two positions on opposite sides of a dead center position lower than either of said two positions, one position of the swinging arms being such as to hold the wheel treads above the lower surface of the runners and the other position of the swinging arms being such as to hold the wheel treads below the lower surface of the runners, the arrangement being such that when said arms are released with the arms in either of said two posi-

tions and with the carriage tipped upwardly to substantially vertical position above the upwardly turned ends of the runners the arms are adapted to swing past the dead center position so as to be brought to the other of said two positions and to be locked releasably in such other position.

2. In a carriage, a pair of runners upwardly turned at one end, a frame structure carried by the runners, a pair of swinging arms each pivoted at one end to opposite sides of the frame structure remote from the curved up ends of the runners, a pair of wheels, one mounted near the swinging end of each of said swinging arms, means interconnecting said arms to cause them to swing together, and means for locking the swinging arms in a position on one side of the dead center position with the wheel treads extending below the bearing surfaces of the runners or alternatively in a position on the other side of the dead center position with the wheel treads raised above the bearing surfaces of the runners, said locking means comprising a notched member attached to move with said swinging arms and having a face portion concentric with the axis about which said arms swing, and detent means adapted by engagement with a notch in said member to hold said member in either of said two positions and adapted to be held out of locking engagement with said notched member at all intermediate positions of the arms between said first named two positions, the arrangement being such that when the carriage is tipped upwardly into substantially vertical position above the upwardly turned ends of the runners with the arms in either of said two positions the arms when released are adapted to swing past the dead center position so that the weight of the carriage on the wheels when the carriage is brought back to normal position causes the arms to be moved into the other of said two positions so as to be releasably locked in such other position by said locking means.

3. In a carriage, a pair of runners upwardly turned at one end, a frame structure carried by the runners, a pair of swinging arms each pivoted at one end to opposite sides of the frame structure, a pair of wheels one mounted near the swinging end of each of the swinging arms, means interconnecting the swinging arms to cause them to move to the same angles in parallel planes, a plate attached to one of the arms having two notches therein, a detent adapted to engage each of the notches in said plate, one notch of said plate being located so as to register with the detent when the swinging arm is moved toward the upwardly turned end of the runner, the other notch in said plate being located in such a position as to register with the detent when the swinging arm is moved to a position away from the upwardly turned end of said runners, one of said notches being positioned to hold the tread of the wheel above the lower surface of the runner when the detent registers with the notch, the other of said notches being positioned to hold the tread of the wheel below the lower surface of the runner when that notch registers with the detent, and means to withdraw the detent from engagement with either notch to permit the arms and wheels to swing like a pendulum from either position of registration to the other position of registration when the carriage is tilted on the upwardly turned ends of the runners sufficiently to permit the wheel treads to clear the ground as the pivoted arms and wheels swing from one position to the other.

4. In a carriage, a pair of runners, a frame structure carried by the runners, a pair of swinging arms, a pair of wheels, one mounted near the swinging end of each of said swinging arms, the opposite end of each swinging arm being pivoted to the frame structure, means for locking the swinging arms in either of two positions on opposite sides of a lower dead center position, one locking position of the swinging arms being such as to hold the wheel treads above the lower surface of the runners and the other locking position of the swinging arms being such as to hold the wheel treads below the lower surface of the runners, a spring against which one of said swinging arms abuts when the arm is locked with the wheel tread below the lower surface of the runners, the spring being compressed by the weight of the carriage and its load upon the wheels, and means to release the arm from said locked position when one end of the carriage is lifted whereby reaction of the spring assists gravity to cause the swinging arms and wheels carried thereby to swing like a pendulum past the lower dead center.

5. In a carriage, a pair of runners, a frame structure carried by the runners, a pair of swinging arms each pivoted at one end to one of the opposite sides of the frame, a pair of wheels one mounted near the swinging end of each of the swinging arms, the swinging arms being adapted to swing from a position substantially parallel with the base of the runners past the lower dead center to a position at a substantial angle above the plane of the runners, a pair of abutments on one of said swinging arms, one located substantially the same distance from the pivot for said swinging arm as the axis of the wheel carried by the swinging arm, the other of said abutments being located at a greater distance from the pivotal support for said swinging arm, said abutments being located in different horizontal planes, one abutment being on substantially the horizontal line of the axis of the wheel when the weight of the carriage is on the wheel and the second abutment being considerably above the first abutment, and a pair of stops having slots into which said abutments snugly fit.

6. In a carriage, a pair of runners, a frame structure carried by the runners, a pair of swinging arms each pivoted at one end to one of the opposite sides of the frame, a pair of wheels one mounted near the swinging end of each of the swinging arms, the swinging arms being adapted to swing from a position substantially parallel with the base of the runners past the lower dead center to a position at a substantial angle above the plane of the runners, a pair of abutments on one of said swinging arms, one located substantially the same distance from the pivot for said swinging arm as the axis of the wheel carried by the swinging arm, the other of said abutments being located at a greater distance from the pivotal support for said swinging arm, said abutments being located in different horizontal planes, one abutment being on substantially the horizontal line of the axis of the wheel when the weight of the carriage is on the wheel and the second abutment being considerably above the first abutment, and a pair of springs one for engagement by each of said abutments.

7. In a carriage, a pair of runners, a frame structure carried by the runners, a pair of swinging arms each pivoted at one end to one of the opposite sides of the frame, a pair of wheels one mounted near the swinging end of each of the

swinging arms, the swinging arms being adapted to swing from a position substantially parallel with the base of the runners passed the lower dead center to a position at a substantial angle above the plane of the runners, a pair of abutments on one of said swinging arms, one located substantially the same distance from the pivot for said swinging arm as the axis of the wheel carried by the swinging arm, the other of said abutments being located at a greater distance from the pivotal support for said swinging arm, said abutments being located in different horizontal planes, one abutment being on substantially the horizontal line of the axis of the wheel when the weight of the carriage is on the wheel and the second abutment being considerably above the first abutment, a pair of housings each having a slot into which said abutments respectively snugly fit, and a spring in one of said housings for compression by one of said abutments.

8. In a carriage, a pair of runners, a frame structure carried by the runners, a pair of swinging arms each pivoted at one end to one of the

opposite sides of the frame, a pair of wheels one mounted near the swinging end of each of the swinging arms, the swinging arms being adapted to swing from a position substantially parallel with the base of the runners passed the lower dead center to a position at a substantial angle above the plane of the runners, a pair of abutments on one of said swinging arms, one located substantially the same distance from the pivot for said swinging arm as the axis of the wheel carried by the swinging arm, the other of said abutments being located at a greater distance from the pivotal support for said swinging arm, said abutments being located in different horizontal planes, one abutment being on substantially the horizontal line of the axis of the wheel when the weight of the carriage is on the wheel and the second abutment being considerably above the first abutment, a pair of housings each having a slot into which said abutments respectively fit, and a spring in each housing for compression by said abutments.
